(57) **CLAIM**

The ornamental design for a folding stool, as shown and described.

DESCRIPTION

FIG. 1 is a front, right and top perspective view of a folding stool, showing our design, with the handles lifted up.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 2.

FIG. 11 is another front, right and top perspective view of the folding stool with the handles down.

FIG. 12 is another front, right and top perspective view of the folding stool folded state; and,

FIG. 13 is another front, right and top perspective view of the folding stool unfolded state with the lid opened.

The broken lines depict portions of the folding stool that form no part of the claimed design.

The dot-dash broken lines in FIGS. 1, 2, 9 and 10 depict the boundaries of the enlargements that form no part of the claimed design.

1 Claim, 13 Drawing Sheets
